TIME INDICATING DEVICE

Irving Greenblatt, New York, N. Y.

Application November 8, 1954, Serial No. 32,986

Term of patent 7 years

(Cl. D1—2)

I claim:

The ornamental design for a time indicating device, substantially as shown.

Fig. 2
